UNITED STATES PATENT OFFICE.

WILLIAM T. SHUTE, OF GLOUCESTER, MASSACHUSETTS.

PACKAGE STRINGING AND TYING MACHINE.

SPECIFICATION forming part of Letters Patent No. 431,080, dated July 1, 1890.

Application filed February 14, 1890. Serial No. 340,417. (No model.)

To all whom it may concern:

Be it known that I, WILLIAM T. SHUTE, a citizen of the United States, and a resident of Gloucester, in the county of Essex and State 5 of Massachusetts, have invented new and useful Improvements in Package Stringing and Tying Machines, of which the following, taken in connection with the accompanying drawings, is a specification.

10 This invention relates to improvements in machines for stringing and tying packages of any kind, and it is carried out as follows, reference being had to the accompanying drawings, wherein—

15 Figure 1 represents a perspective view of the machine. Fig. 2 represents a front view of it. Fig. 3 represents a cross-section of the machine; and Fig. 4 represents a detail perspective view of the locking device for holding the revolving frame in position while 20 tying the strings around the packages, as will hereinafter be more fully described.

Similar letters refer to similar parts wherever they occur on different parts of the drawings.

25 The machine consists of a rotary frame, preferably composed of package-supporting radial plates or boards A A and string-holding radial plates or boards B B, as shown in the drawings, which plates or boards are firmly 30 secured together in any suitable or desirable manner and provided at their adjoining central portions with pins C C, loosely journaled in bearings D D, secured to a suitable table or work-supporting plate E, as shown. The

35 outer edges of the radial boards or plates A B are provided with notches or slits a a and b b for the reception of the tying-strings f f, by means of which the packages are tied.

Between each of the plates or boards A B 40 is secured in a suitable manner a longitudinal bar G, having string-receiving notches or slits g g, arranged opposite the notches or slits a b on the respective radial boards or plates A B, as shown. The bars G G are preferably secured to triangular bars G' G', secured to the boards or plates A B, as shown in Figs. 1 and 3; but this is not essential, as the notched or slotted bars G G may be secured to the boards or plates A B, or any one 45 50 of the same, in any other suitable or equiva-

lent manner without departing from the essence of my invention.

At the junction of the radial boards or plates A B, I prefer to secure longitudinal bars H H, which serve as back-rests for the 55 packages I that are to be strung and tied.

To one end of the plates or boards A B is secured a lateral disk or plate K, which serves as an end support against which the first package is placed preparatory to its being 60 strung and tied, as shown in Fig. 1. To the top of the table E is secured in a suitable manner a tension and string guide-bar L, having slits or notches l l, for the purpose of guiding the tying-strings to the notched rotary frame. 65

Below the table E is arranged in bearings a horizontal shaft F, on which is loosely journaled side by side a series of reels F' F', containing the strings or cords f f by means of 70 which the packages are to be tied.

For the purpose of securing the rotary frame in position while tying the packages, I secure to one of the bearings D or other stationary part of the machine a spring-bar 75 M, the upper end of which is adapted to be locked in notched locking-plates k k, secured to the outside of the end plate K, as shown in Figs. 2 and 4, said spring having in its upper end a handle m for the purpose of 80 locking and unlocking said spring-bar M from the said notched locking-plates k k.

The operation of the machine is as follows: The strings f f are placed in the notches or slits of the plates A, B, and G, as shown in 85 Figs. 1 and 3, and the rotary frame is swung until the plates or boards A A are held and locked in a horizontal, or nearly so, position, as shown in the drawings. The operator then takes a knife N (shown in Fig. 1) and guides 90 it against the upper side of that one of the slotted bars G, which is for the time being back of the rotary frame, by which all the strings are cut off at this place. After the strings have been cut off, as above mentioned, 95 the operator takes one package I after another and places them on the plate A and against the guide-bar H, as shown in Fig. 1, the first package being placed with its end against the end plate K, as shown in said Fig. 100

1, and the others, one or more, abutting against each other end to end, until the whole length of the board or plate A is filled with packages. As the said packages I are placed in 5 position on the board or plate A the severed strings *ff* are pressed into the angle of the said plate and the back-rest H, after which the ends of the said strings are tied around the packages I, as shown at the right-hand 10 end of Fig. 1. After all the packages on one of the boards or plates A have been tied, as above described, they are removed, the spring-bar M is unlocked from the notched locking-plates *k* on the end plate K, and the frame 15 A B swung half a revolution around its axis, in the direction shown by arrows in Figs. 1 and 3, and again locked in position, as before, after which the strings *ff* are again cut by means of the knife N, drawn against the upper front side of the bar G, and a new lot of 20 packages I placed in position on the radial plate or board A, and so on during the operation of the machine.

The boards A B may be long enough to contain one or more of the packages to be tied, 25 and any suitable number of strings may be used for tying each package, as may be desired, according to the nature, length, or dimension of the packages to be strung and tied.

I wish to state that I do not confine myself 30 to two plates or boards A A for supporting the packages while being tied, as any suitable number of the same may be used without departing from the essence of my invention. Neither do I wish to confine myself to the use of reels F F, as shown, as balls of 35 twine or strings arranged in baskets or receptacles below the table E may be used to equal advantage.

For certain purposes wires may be used instead of string for the purpose of tying the packages, if so desired.

What I wish to secure by Letters Patent, and claim, is—

1. The stringing and tying machine, as described, consisting of a rotary frame composed of notched or slotted package-supporting plates A A, slotted or notched plates B B, and slotted or notched guide-bars G G for cutting off the strings, substantially as and for the purpose 45 set forth.

2. The stringing and tying machine, as described, consisting of a rotary frame composed of notched radial plates A B, and intermediate notched ribs G, combined with a package-supporting back-rest H and end plate K, having means, substantially as described, for securing it in position while the packages are being strung and tied, as and for the purpose 50 set forth.

3. The stringing and tying machine, as described, consisting of a rotary frame composed of slotted or notched radial plates A B, intermediate slotted or notched ribs G G, and a locking and releasing device on said rotary 55 frame, combined with a stationary slotted or notched tension-bar L, and a series of reels F F, substantially as and for the purpose set forth.

In testimony whereof I have signed my 60 name to this specification, in the presence of two subscribing witnesses, on this 11th day of February, A. D. 1890.

WILLIAM T. SHUTE.
